UNITED STATES PATENT OFFICE.

CLEOPHAS MONJEAU, OF MIDDLETOWN, OHIO.

SAND-SCREEN.

SPECIFICATION forming part of Letters Patent No. 482,020, dated September 6, 1892.

Application filed September 24, 1891. Serial No. 406,639. (No model.)

To all whom it may concern:

Be it known that I, CLEOPHAS MONJEAU, a citizen of the United States, residing at Middletown, Butler county, Ohio, have invented new 5 and useful Improvements in Sand-Screens, of which the following is a specification.

My invention relates to "sand-screens," and particularly to the class of screens in which the screening-apertures are circumferential 10 slits made in a tubular body, its object being to produce an inexpensive and efficient screen of novel construction, great capacity, and resisting strength, one feature of which is of 15 general application as an improvement to screens of the same constructive type to increase the water capacity.

To this end my invention consists in a sand-screen composed of a cylindrical tube of metal, provided interiorly upon its inner periphery 20 with independent longitudinal supporting-ribs and having a series of circumferential screening-slits cutting through and entirely around the cylindrical shell; and it further consists in a series of longitudinal grooves 25 sunk partially but not entirely through the tubular body crossing the circumferential slits. This latter feature of my invention may be employed upon all sand-screens of the general type having circumferential slits as 30 an independent feature, while also the first-mentioned construction may also be used independently of the second, although the best results are attained in the use of both together.

35 Mechanism embodying my invention is illustrated in the accompanying drawings, in which—

Figure 1 is an external view of my improved screen complete; Fig. 2, a perspective 40 view of part of the tubular body, showing the interior construction; Fig. 3, an enlarged detail section in the plane of one of the horizontal screening-slits; Fig. 4, an enlarged detail section in the plane of one of the vertical feed-grooves; Fig. 5, an enlarged diagram exhibiting the boundaries of the general water-aperture (in an isometric plane) formed by one 45 of the circumferential slits with its feed-grooves, showing the increased capacity. Fig. 50 6 is a screen embodying my invention of a type in which the tubular cross-slitted body is composed of a strip or strips wound spirally

upon a perforated hollow case; and Fig. 7 is an enlarged detail section in the plane of one of the longitudinal feed-grooves, showing construction. 55

Referring now to the drawings, the screen A, consists of a cylindrical shell A', a head or cap A², and a "point" A³. The shell A' is a hollow cylinder provided with independent 60 interior longitudinal supporting-ribs a, which are preferably drawn with the tube in the process of manufacture. To constitute the screen, continuous circumferential slits b are sawed or cut through the cylindrical shell 65 and partly through the supporting-ribs a, as indicated in Fig. 3. The intact portions of the ribs constitute a support for the screen, which still maintains its general cylindrical form. The screening-slits thus made are continuous circumferentially. They may be in 70 parallel planes at right angles to the axis, or a single spiral slit continuous throughout. Thus constructed the screen is easily and cheaply made and is effective for the purpose. 75

A further feature of my invention consists in increasing the water-receiving capacity of a screen of this general character as follows: Across the circumferential slits, however made, is cut a series of parallel longitudinal 80 recesses or grooves c, extending into the surface of the shell, say, to one-half of its thickness. These cross the first-named slits b and increase its receiving area, as shown in an isometric plane in Fig. 5. The increase is more 85 perceptible in those screens in which the screening-slit widens inwardly, an example of which is exhibited in Figs. 6 and 7. Here the tubular body of the screen is composed of strips of proper section, as d, Fig. 7, wound 90 spirally upon a suitable perforated hollow core e, with an intervening perforated separating-strip f. The longitudinal grooves c are cut to the depth of the separating-strips, as shown.

As the screening-slits and feed-grooves are 95 exceedingly minute, they both serve to screen out the sand and admit the water.

The practical advantage of the improvement will be readily understood if we conceive of the water capacity of the screening-slit interfered with by the lodgment of particles of sand at its outer margin too large to pass between, but held there by the inner suction and obstructing the free entrance of water. Now 100

the longitudinal grooves being of the same width as the screening-slits also screen the sand, but permit the water to flow into the screening-slit through their intersecting openings, thus practically nearly doubling the water capacity.

I claim as my invention and desire to secure by Letters Patent of the United States—

1. A sand-screen consisting of a continuous cylindrical tube or shell of metal formed with a series of longitudinal ribs upon its inner periphery integral with the cylindrical shell and provided with circumferential screening-slits extending entirely around and through the

shell, leaving the supporting - ribs substantially intact, substantially as set forth. 15

2. In a sand-screen of the general type embodying a tubular shell cut through by screening-slits, a series of cross-grooves cut partially through the shell across the screening-slits, 20 substantially as set forth.

In testimony whereof I have hereunto set my hand in the presence of two subscribing witnesses.

CLEOPHAS MONJEAU.
